UNITED STATES PATENT OFFICE.

JACOB GOLDSTEIN, OF WEST HAZLETON, PENNSYLVANIA.

FOUNTAIN-PEN BLOTTER.

1,291,835.

Specification of Letters Patent.

Patented Jan. 21, 1919.

Application filed October 2, 1918. Serial No. 256,565.

To all whom it may concern:

Be it known that I, JACOB GOLDSTEIN, a citizen of the United States, residing at West Hazleton, in the county of Luzerne 5 and State of Pennsylvania, have invented certain new and useful Improvements in Fountain-Pen Blotters, of which the following is a specification.

This invention relates to stationery, and 10 more especially to blotters; and the object of the same is to carry a blotter upon the cap which usually covers the pen point of a fountain pen.

My invention is carried out by mounting 15 upon said cap a metal cylinder which contains the blotter, and mounting on the cylinder a supplemental cap for covering the same, but it is obvious that the main cap of the pen could itself take the place of 20 the cylinder, and I wish my idea to be as broadly considered.

Details of the preferred manner of carrying out the invention are set forth in the following description and claims and attention is drawn to the drawings, wherein—

Figure 1 is an elevation of a fountain pen provided with this attachment.

Fig. 2 is an enlarged vertical section of the upper portion thereof on the line 2—2 30 of Fig. 1.

Figs. 3 and 4 are cross sections on the lines 3—3 and 4—4 of Fig. 2.

Fig. 5 is an elevation of the metal portion or cylinder removed from the ordinary cap.

In the drawings, I have used the letter B 35 to designate the barrel of the fountain pen which is usually of hard rubber, and P is the pen point itself. C is the cap which usually covers this point and closes this end of 40 the barrel when the same is not in use, and this cap is generally also of hard rubber. Sometimes the cap carries the spring clip S, and sometimes it is mounted on the barrel. In the present case, as the cap is of 45 metal, I make it an integral part of my attachment which also is of metal.

Coming now to the details of the invention, the numeral 1 designates the body which is substantially cylindrical and is of 50 metal. By preference it is crimped along opposite sides to form two longitudinal grooves 3 which will of course produce ribs 4 on the exterior. At its lower end 5 it may be clipped or otherwise fastened around or 55 to the cap C, and by preference I make its lower end into the form of a spring clip, as

shown at S. The upper and lower ends of the body are open, excepting that its lower end is closed by the upper end of the cap C. The numeral 6 designates a wire bent substantially into a rectangle. Its center extends across the body 1 as shown at 7 in Fig. 2, its arms 8 rise from said bent center and stand within the grooves 3, and its ends are interned as shown at 2 and form the 60 bearings for a small roller 10 whose exterior is covered with blotting material. This wire may be slipped into the grooves, but by preference I solder or otherwise secure it therein.

The numeral 11 designates a metal cap closed at its upper end as at 12 and provided along its sides with internal grooves 14 which of course produce external ribs 15. This cap is to be slipped over the body, and 70 its grooves 13 slide onto the ribs 4 thereof. The body is by preference provided around its mid-length with a shoulder 15 against which the lower end of the cap rests when the parts are in place, and at this time the 75 upper end 12 of the cap does not quite touch the blotting roller 10. However, I have described the cap as of hard rubber and the attachment of metal and when so made it will doubtless be the attachment which will 80 carry the spring clip S.

The use of the device is obvious. After having written and at a time when cap C is off the pen, it is quite easy for the user to withdraw the cap 11 and blot his signature by running the little roller over it.

The foregoing description and the drawings have reference to what may be considered the preferred or approved form of my invention. It is to be understood that I may 90 make such changes in construction and arrangement and combination of parts, materials, dimensions, et cetera, as may prove expedient and fall within the scope of the appended claims.

Having thus fully described my invention, what I claim as new and desire to secure by Letters Patent, is:—

1. In a device of the class described, the combination with a cylindrical body having ribs on its opposite sides producing internal grooves; of a wire bent into parallel arms secured within said grooves and their outer ends extending beyond said body and in-turned into trunnions, a roller rotatably mounted on said trunnions and having a blotting surface, and a cap slidably mounted on

said body for inclosing the roller when not in use.

2. In a device of the class described, the combination with a cylindrical body having 5 ribs on its opposite sides producing internal grooves; of a wire bent into parallel arms secured within said grooves and their outer ends extending beyond said body and in-turned into trunnions, a roller rotatably 10 mounted on said trunnions and having a blotting surface and a cap having a cylindrical body with opposite grooves for slidably engaging said ribs, the outer end of the cap being closed.
- 15 3. In a fountain pen blotter, the combina-

tion with a tubular body for attachment to the barrel cap, the body being of metal and having longitudinal internal grooves and an external shoulder around its mid-length; of a roller having a blotting surface, a wire 20 support for said roller having arms mounted within said grooves, and a metal cap slidably mounted on the body and inclosing the roller when not in use.

In testimony whereof I affix my signature 25 in presence of two witnesses.

JACOB GOLDSTEIN.
